*Primary Examiner—A. Hugo Word**Assistant Examiner—E. Watterson**Attorney, Agent, or Firm—H. Jay Spiegel***[57] CLAIM**

The ornamental design for a combined toilet and fluid motor seat lifter, as shown and described.

DESCRIPTION

FIG. 1 shows a front perspective view of the present invention;

FIG. 2 shows a side view of the present invention;

FIG. 3 shows the other side view of the present invention;

FIG. 4 is a top view of the claimed design;

FIG. 5 shows a front elevational view of the claimed design; and,

FIG. 6 shows a rear elevational view of the claimed design.

FIG. 1

FIG. 2

FIG. 3

FIG. 4

FIG. 5

FIG. 6
